ARTICLE OF MANUFACTURE FOR SHOES

Application filed May 19, 1928. Serial No. 278,928.

This invention relates to improvements in the structure of shank-stiffeners such as employed in shoes of the so-called hygienic or orthopaedic type whereby, without changing 5 their unitary nature, a more efficient and desirable article may be produced at little if any advance over the cost of ordinary shank-stiffeners.

Most shank-stiffeners go no further than 10 to provide stiffness for the shank of the shoe, and thereby support for only the main, or "plantar" arch of the foot, and what is more deplorable since they stiffen all parts of the shank indiscriminately, some parts of the 15 plantar arch, particularly the outer side, where stiffening is quite detrimental, will be forced into cramped or distorted positions thereby.

It is an object of the present invention to 20 provide a shank-stiffener having such a formation and structure that those parts of the plantar arch particularly the innerside muscles which need most support, will receive it; and at the same time, the other parts which 25 require less support yet nevertheless need a certain kind of supporting that will not interfere with the flexing and relaxing of these parts, will be so supported as to take care of their particular needs.

30 The metatarsal arch, that is, the transverse arch between the large toe and the small toe in the ball of the foot, is just as often the cause of foot discomfort and trouble as is the plantar arch, and it is a further object 35 of the present invention to provide a single, essentially unitary article of manufacture for furnishing the above mentioned differential improved support to the plantar arch, at the same time providing the different kind of support the metatarsal arch requires.

The invention will be described in connection with the accompanying drawings, wherein for the purpose of illustration:

45 Fig. 1 is a longitudinal sectional view of the finished shank-stiffener;

Fig. 2 is a perspective view of the metal body-portion;

50 Fig. 3 is a perspective view of the outer or covering portion of the shank stiffener, removed from the body-portion;

Fig. 4 is an assembly view of the two parts of the article in the unitary form in which it is used;

Fig. 5 is a perspective view of a modified form of body-portion;

Fig. 6 is a perspective view of the covering part for this form of body portion;

Fig. 7 is a perspective view of the complete shank-stiffener;

Fig. 8 is a view of the article in place in a shoe;

Fig. 9 is a plan of Fig. 8;

Fig. 10 is a section on line 10—10 of Fig. 8, and

Figs. 11, 12 and 13 are modified forms of the body-portion.

Referring now in detail to the parts of the invention shown in the drawings, the body portion is stamped out of flat metal, preferably spring steel and comprises a forward end 1 and a rear end or heel-flat 2, and an intermediate, or shank portion. The shank-stiffener arches upwardly and rearwardly from the forward end toward the rear end thereof to conform to the shape desired for the arch or shank portion of a shoe and extends from the rear end of the tread of the sole of the shoe, to a point vertically above the heel, so that it may be attached to the heel by tacks or the like.

At its forward end, the body has a formation comprising a table or ledge section, here shown as approximately a triangle 6, outlined and defined at its inner edges by the bend lines 7, which diverge from a point 8, this point 8 being the forward end of the shank portion of the body, and being formed at the forward terminal of the downwardly projecting ridge 9, which extends lengthwise of the shank stiffener.

It is to be understood that the metal on both sides of this ridge 9 can be flattened out to fit level against the shoe inside so as not to present upwardly facing or peaked edges which would cut the shoe leather. Or, if desired, one side may be so flattened and the other side left bulging upwardly, as shown in Figs. 2 and 4, where only the inner side 14 is shown flattened. It is preferred to always flatten the inner side, in order to prevent

throwing the weight of the body to the outside of the shank-stiffener, and hence on to the fifth metatarsal bones, which undesirable action would result if the inner edge 14 were allowed to project upwardly at the same angle which it has at the bottom of the ridge.

The body, or base, portions are made in rights and lefts for pairs of shoes, with the inner side of the table section 6, at the tread or ball, prolonged more than the outer side, as shown at 10, thereby conforming to the shape of the shoe at the juncture of the tread and instep. The table section 6 and the flat heel part 2 provide a broad lateral support for the stiffener at each end and prevent the stiffener from twisting under the weight of the arch. The portion 14 of the shank of the body, which lies to the inward of the center line or ridge 9, is left solid and whole but with just the necessary amount of flexibility, while the portion 15 of the shank to the outward of the center line, is completely cut away from the point 16, where the upward curve of the arch begins, to the point 17, where it ends, but leaving an outwardly curved inner edge 28, which is serrated as shown at 29. This serration consists of a plurality of notches 29', the roots of which lie on a curved line to the inside of the center line, their shape and location conferring the proper transversely yielding support to that portion of the foot which lies just over the center-line on the outside of the arch, particularly the bone on the outside of the foot which, unlike the other bones of the foot, has its tarsal point close to the sole of the foot at the instep. Thus that part of the planter arch which more than any other tends to become flat, that is the abductor region, is protectively supported upward in proper arch form, instead of being left unaided to hence fall or become deformed, as in a supporter flexible throughout, while the extreme outer side of the plantar arch, particularly in the region of the fifth metatarsal bones, is hereby left unimpeded and free to rest flat in the shoe, instead of being held up in an arch, or otherwise "bound" or cramped in action, as would occur with a supporter made rigid throughout.

The member 14' at each end of the serrations 29 is provided with locking slots 19, the serrations and locking slots serving to hold in place a pad 20 of rubber or other resilient elastic material, shaped as shown into a tongue 21 and a shank 22. This pad extends beyond the table portion at the forward end. This pad may be molded right on the shank-stiffener, or may be molded separately from the stiffener and provided with suitable projections 40 interlocking with the serrations 29 and slots 19. The pad when separately molded is also provided with a sheath 23 adapted to engage the forward edge of the table.

The rubber pad portion 20 serves two important functions. Primarily it serves to support the transverse, or metatarsal, arch of the foot. To this end the upper surface of the pad at its forward end is convex and its point of greatest thickness is positioned so as to come under the middle of the ball of the foot as shown more particularly in Fig. 10, thereby causing the bones of the foot to spread apart rather than to be pressed together when the weight comes on the foot. In walking without shoes the foot naturally tends to spread as the weight comes on it, but when confined in a shoe, particularly a shoe with a light sole which can bend upward along the side edges, the sole of the shoe tends to assume a concave shape on the inside so that the greater thickness of the flesh at the middle of the foot is insufficient to hold up the transverse arch, hence the bones at the middle tend to flatten down to the same horizontal plane as the other bones of the foot, thereby pressing the bones together, causing considerable discomfort, particularly in shoes that fit snugly.

The shank portion of the pad serves principally to fill in the concave or V-shaped upper side of the stiffener. In order to give sufficient strength to the stiffener without undue weight, the upper face of the shank is pressed down at the middle, forming the ridge 9. This leaves the upper face of the stiffener concave to a greater extent than desirable. By extending the pad up the shank of the stiffener in the manner shown, this concavity is filled in and the edges of the shank are covered, thereby providing a yielding support for the foot at the instep, particularly along the outer side of the foot where the prominence of the bone makes a cushion particularly desirable.

This shank portion of the pad is not so essential in the form shown in Figs. 6 and 7, as the shank of the stiffener is narrower, while the central depression is more in the nature of a central longitudinal rib and the concavity on the upper surface not so pronounced. With this form of stiffener the shank of the pad may be extended no farther back than necessary to be securely anchored on the stiffener in the manner shown.

In Figs. 11, 12 and 13 I have illustrated certain modifications of my improved shank stiffener wherein flexibility of certain portions of the stiffener is provided without unduly weakening the stiffener as a whole. These modified forms of stiffeners may be used either with or without the rubber pads.

The stiffener shown in Fig. 12 is of the same type as the stiffener shown in Fig. 6, except that the table or triangular portion 6 at the forward end of the stiffener is slotted as shown at 50, thereby dividing the platform into a series of tongues 51. The slots may be formed when the blank is stamped

out or they may be cut in a previously formed stiffener of the kind shown in Fig. 6. The metal of the stiffener will be tempered after the slots are formed so that each tongue 51 constitutes a separate flat spring capable of yielding slightly in either direction as the shoe is bent in walking. The slots 50 do not extend through the angles or corners at the juncture of the table with the main portion of 10 the stiffener, consequently the stiffener will not be distorted permanently out of its normal shape, the tongues merely providing what may be termed a "local" flexibility in the table portion itself.

15 In Fig. 11 I have shown a form of stiffener wherein the main arch of the stiffener is rendered flexible by spaced slots 52 extending from each edge of the stiffener to the central ridge but not through the ridge. 20 These slots allow the stiffener to twist slightly and also to give slightly on one side or the other under uneven pressure. As the slots, however, do not cross the rib, the strength of the arch is not materially impaired and the 25 stiffener cannot be permanently flattened or otherwise distorted out of its original shape.

In Fig. 13 I have shown a stiffener having the flat table portion slotted as shown in Fig. 12 and the arch portion also slotted as shown 30 in Fig. 11 to thereby combine in a single stiffener a flexible table portion and a flexible arch portion. As both the longitudinal rib and the angles or corners 7 between the table and the arch portion are solid, the stiffener 35 will hold its shape but will permit local yielding and bending without permanent distortion.

The cost of my improved shank-stiffener over an all-metal stiffener is negligible compared with the cost of a pair of shoes, amounting to little more than the actual cost of the rubber in the pad. The improvement, however, is marked. The principal objection heretofore raised to the so-called hygienic, 40 or orthopaedic, shoes, has been that such shoes are too stiff and hold the foot too firmly in one position. My improved arch support is much more flexible than the ordinary arch support, but it is nevertheless strong enough 45 to support the instep in its natural arched position. The pad also is a distinct improvement, providing not only a support for the transverse arch of the foot, but also a cushion over the unyielding metal of the stiffener, 50 thereby adding to the comfort of the shoe, as well as to its durability.

I claim:

1. As a new article of manufacture, a unitary shoe member having a portion for fitting 55 under the plantar arch and an extension for fitting under the metatarsal arch, said portion for fitting under the plantar arch comprising a comparatively rigid part on the inside of the arch and a yielding part on the 60 outside.

2. A shoe-shank stiffener of the character described having at its forward end a broadened section conformed to the rear end of the tread portion of the shoe, and having a central longitudinal ridge extending throughout most of its body portion, the body portion to one side of said ridge being cut away in such a manner as to provide the shank-stiffener with an opening on one side sufficient to accommodate the outside of the plantar arch. 70

3. A shoe-shank stiffener of the character described having at its forward end a broadened section conformed to the rear end of the tread portion of the shoe, and having a central longitudinal ridge extending throughout most of its body portion, the material on most of one side of said ridge being cut away, the remaining edge of said longitudinal ridge being curved outwardly and serrated transversely in its center. 80

4. As a new article of manufacture, a shank-stiffener comprising a metal arch and a member of resilient material, said member having a shank and a tongue, said shank 90 having formations on its under side for fitting into and engaging with said metal arch and said tongue extending beyond said stiffener and having a formation to adapt it to fit under and support the metatarsal arch 95 of the foot.

5. As a new article of manufacture, a pad for metal shank-stiffeners formed of resilient material, and having a shank portion and a tongue-portion turned relatively upward 100 therefrom, said shank-portion extending over a part of the length of said shank-stiffener and having a smooth upper surface and formations on its lower surface for engaging with said shank-stiffener, said tongue portion extending beyond said table and having a smooth upper surface, a sheath-like opening at the turn of the tongue-portion from the shank for engaging over the front edge of said stiffener, a rounded protuberant 110 upper surface, and a substantially triangular periphery for fitting under the metatarsal arch of the foot. 105

6. A metal shank-stiffener comprising an upwardly arched sheet metal member having a central ridge, the metal on one side of said ridge being transversely slotted to form a plurality of separate elastic tongues. 115

7. A metal shank-stiffener comprising an upwardly arched sheet metal member having a central rib, the metal on one side of said rib being transversely slotted to form a plurality of separate elastic tongues, said shank-stiffener having at its forward end a flat table portion for projecting into the tread portion of the shoe, said table portion being longitudinally slotted to provide a plurality of separate spring tongues. 120

8. As a new article of manufacture, a unitary shoe member having a portion for fitting 130

under the plantar arch, said portion for fitting under the plantar arch comprising a comparatively rigid part on the inside of the arch and a yielding part on the outside.

5 9. A pad for shank-stiffeners which have an upwardly concave body-portion and a table portion turned relatively upwardly from the body portion, comprising a piece of material having a portion for fitting into 10 and lock-engaging with the concave body-portion and having another portion engaging over the table-portion and forming an extension for said shank-stiffener.

In testimony whereof I affix my signature.
FRANK G. DELBON.
